UNITED STATES PATENT OFFICE.

ROBERT E. PATTEN, OF BOWDOINHAM, MAINE.

SNOW-SCRAPER.

SPECIFICATION forming part of Letters Patent No. 289,181, dated November 27, 1883.

Application filed August 21, 1883. (No model.)

To all whom it may concern:

Be it known that I, ROBERT E. PATTEN, a citizen of the United States, residing at Bowdoinham, in the county of Sagadahoc and 5 State of Maine, have invented certain new and useful Improvements in Snow - Scrapers, of which the following is a specification, reference being had therein to the accompanying drawings.

10 My invention relates to scrapers such as are used to remove snow from the surface of the ice; and the object of my invention is to provide a scraper which can be handled by one man, instead of three, as those in common 15 use now require, and which may be easily drawn to any required distance after being loaded. I accomplish this result by means of the device shown in the accompanying drawings, in which—

20 Figure 1 shows a perspective view. Fig. 2 shows a side view. Fig. 3 shows a longitudinal section through the center.

A A are two sled-runners, united by the cross-bar B and the drawing-bar C. These 25 runners are built up to a considerable height forward, the forward portion being filled in solid.

E is a scraper, made in the form of a box having one end removed. The rear end of 30 the scraper E sits on the cross-bar B, and the pin P, fixed in the edge of the scraper, prevents it from sliding backward. On the lower edge of the scraper is secured the shoe or cutter L, made of metal or other suitable material. The box E contains a sliding bottom, e, which is arranged to slide backward until stopped by the pegs R. This bottom e rests on the cross-piece K, which is attached to the bottom of the box-scraper E, and on 35 the bar J, which is attached to the middle of cross-piece K and extends backward, resting on the cross-bar B. The cross-piece e' is joined to the rear of the sliding bottom e by means of cleats, and a space is left between it and the bottom large enough to insert a 40 handspike.

On the outside of each sled-runner are the stanchions D D, and resting in bearings on the tops of these stanchions is the shaft F, near 45 each end of which is a drum or pulley, G. Around these drums are wound ropes or chains, the lower ends of which are secured to the forward end of the box-scraper E.

The lever I, secured to the end of shaft F 50 by a pivot, extends backward, so that the end

may be placed under the projecting end of cross-bar B. The ropes H H are so arranged that when the end of lever I rests under the cross-bar B the end of the box-scraper E will be raised clear from the ice.

60

When the scraper is to be used, the end of lever I is taken from under the end of cross-bar B and the forward part of the scraper falls to the ice, as shown by dotted lines, Fig.

65 2. As the scraper is drawn forward, it fills itself without manipulation. The high runners increase the capacity of the scraper so long as it is left down. When the load is to be removed to a distance, the lever I is forced down and caught under the end of cross-bar B, thus raising the scraper from the ice and bringing the load on the two runners, in 70 which position it may be moved easily to any distance. When the load is to be dumped, a handspike is inserted between the bar e' and the sliding bottom e and the horses started 75 ahead. The bottom is thus withdrawn, and the load falls through. The stops R prevent the bottom from sliding entirely out. The load is dumped in a better manner than by the ordinary scraper, being smoothly deposited on the ground and not heaped in a pile.

80 My device is capable of being used as a horse-sled as well as a scraper.

85 It will be seen that my scraper may be easily managed by the man who drives the horses, whereas the scraper now in common use requires the labor of three men.

I claim—

1. The snow-scraper composed of runners 90 A A, with their cross-bar B, combined with the box-scraper E, having sliding bottom e, and the hoisting apparatus consisting of lever I, shaft F, pulleys G G, and ropes H H, substantially as described.

95 2. In a snow-scraper, the runners A A, combined with the box-scraper E, with its sliding bottom e, and with its rear end resting on cross-bars B, its forward end being raised and lowered by lever I, substantially 100 as shown and described.

105 3. In a snow-scraper, the runners A A, combined with the box-scraper E, the forward end of which is raised and lowered, substantially as shown and set forth,

In testimony whereof I affix my signature in presence of two witnesses.

Witnesses: ROBERT E. PATTEN,

S. W. BATES,
WILLIAM GARNER.
